UNITED STATES PATENT OFFICE.

CALVIN B. PATCH, OF GLENELLYN, ILLINOIS, ASSIGNOR TO WILLIAM H. MINER, OF CHAZY, NEW YORK.

SIDE BEARING FOR RAILWAY-CARS.

1,178,670.

Specification of Letters Patent.

Patented Apr. 11, 1916.

Application filed October 22, 1914. Serial No. 868,013.

To all whom it may concern:

Be it known that I, CALVIN B. PATCH, a citizen of the United States, residing at Glenellyn, in the county of Du Page and State of Illinois, have invented a certain new and useful Improvement in Side Bearings for Railway-Cars, of which the following is a full, clear, concise, and exact description, reference being had to the accompanying drawings, forming a part of this specification.

This invention relates to improvements in side bearings for railway cars.

One object of the invention is to provide a novel form of side bearing for railway cars, which is of economical construction, efficient operation and so arranged that the anti-friction roller employed therein will automatically return to normal central position each time after it has performed its function.

The invention furthermore consists in the improvements in the parts and devices and in the novel combination of the parts and devices herein shown, described or claimed.

In the drawing, forming a part of this specification, Figure 1 is an elevational view showing a truck bolster and body bolster of a railway car having my improved side bearings attached thereto. Fig. 2 is an enlarged sectional view taken substantially on the line 2—2 of Fig. 1 and illustrating the side bearing in normal position of the parts. Fig. 3 is a vertical sectional view taken substantially on the line 3—3 of Fig. 2 and Fig. 4 is a view similar to Fig. 2 and showing the position of the parts when the side bearing is performing its function.

In said drawing, 10 denotes the body bolster of a car and 11 a truck bolster, which may be of any suitable or well known form. On each side of the king pin uniting the body and truck bolster, my improved side bearing A is employed and each of said bearings, as shown, preferably comprises a bracket or base casting 12 having flanges 13 on the opposite sides thereof by which it is riveted or otherwise suitably secured to a projection 30 formed integrally with the body bolster. The bracket 12 is provided with inner and outer depending side walls 14, each of which in turn is provided with depending arms 15 at the corners thereof. On the upper inner side of the bracket 12, is provided a bearing plate 16, prefer-

ably of steel, which is secured to the bracket proper by means of rivets 17 or other suitable means. Extending through each pair of depending arms 15 is a more or less flexible strip 18 having the ends thereof upturned as indicated at 19, each strip 18 being downwardly inclined from each end to the center thereof and thereby forming inclined tracks with the lowest point at the center on which rides the extended ends 20 of a journal 21. Said journal 21 is preferably rotatably mounted in a pair of journal bearing members 22—22 and secured to said journal between the journal bearing members 22, and extending above the tops of 70 the latter, is an anti-friction roller 23, which, as clearly shown in Fig. 4, is adapted to engage and roll upon the wear or thrust plate 16. Each of the journal bearing members 22 is extended below the bottom of the anti-friction roller 23 and is provided with a flat lower surface 24.

As shown in Fig. 2, in normal position of the parts, the roller 23 is out of engagement with the wear plate 16 and there is also a space between the lower surfaces of the members 22 and the wear or thrust surface 25 formed on the upper side of the truck bolster 11. It will also be noted that the shape and disposition of the metal in 85 the journal bearing members 22 is such that the flat portions 24 will always remain below the axis of the journal 21 and whenever the journal bearing members and the anti-friction roller carried thereby is displaced from the normal central position, said parts will return to normal as an entity, due to the fact that the extended ends of the journal will roll down the inclined track 18 under the influence of gravity. The journal bearing members or supports for the roller are bodily movable and are or may be brought to rest at various positions upon the surface 25 and the roller brought into play against the wear plate 16. With this arrangement, the wear on the two wearing surfaces is distributed over a greater area thereof, thus increasing the life of the bearing and the roller can be brought into play to serve its function as an anti-friction element between the two bolsters at any relative radial position of the bolsters.

I have herein shown and described what I now consider the preferred embodiment of my improvement, but the same is merely 110

illustrative and I am aware that changes and modifications may be made without departing from the spirit of the invention and all such changes and modifications are contemplated as come within the scope of the claims.

I claim:

1. In a side bearing for railway cars, a member provided with a bearing surface, a roller normally separate from but adapted to engage with said surface, a journal for said roller, and bodily movable journal bearings for said journal, said journal bearings being normally suspended from said journal.
2. In a side bearing for railway cars, the combination with a member provided with a bearing surface, of roller supporting members, a roller mounted on said members, said roller and members being bodily movable as an entity, and the roller being adapted to engage said bearing surface when the side bearing is being actuated.
3. In a side bearing for railway cars, in combination with body and truck bolsters each having a bearing surface, of an anti-friction roller, journal bearing members by which said roller is rotatably supported, said members and roller being interposed between said bearing surfaces and normally out of contact therewith, the journal bearing members being bodily movable and adapted to be brought in engagement with one of the bearing surfaces at different points thereon.
4. In a side bearing for railway cars, a roller, journal bearing members, a journal on which said roller is mounted and having its ends extended beyond said members, and inclined tracks on which said extended ends are adapted to ride, whereby said roller and journal bearing members are adapted to return to normal position under the influence of gravity.
5. In a side bearing for railway cars, the combination with a body bolster, of a bracket secured thereto, a roller, supporting

members arranged to be shifted bodily relatively to said bracket and by which said roller is rotatably supported, and means 50 upon said bracket for retaining said roller and supporting members.

6. In a side bearing for railway cars, the combination with a car body bolster of a bracket secured thereto, inclined tracks carried by said brackets, a roller, journal bearing members, and a journal for supporting said roller and having its ends extending through and beyond said bearing members and on said inclined tracks.

7. In a side bearing for railway cars, a bracket adapted to be secured to a bolster, said bracket having a bearing surface, tracks secured to said bracket and having oppositely inclined portions, a roller carried by a journal having the ends thereof adapted to rest upon said inclined tracks, and journal bearing members through which said journal extends, said roller, journal and journal bearing members being bodily movable as a unit.

8. A side bearing for cars comprising, a roller, and bearing members therefor, said bearing members having faces on which they are adapted to rest and having the 75 center of weight of the material forming the same so arranged that said faces are always held downwardly under the influence of gravity.

9. A side bearing for cars comprising a 80 roller, a journal extending through said roller, and journal bearing members in which said journal is mounted, said members having flat surfaces on which they are adapted to rest, the center of weight of the 85 material forming said members being arranged below said journal to thereby always maintain said faces at the bottom under the influence of gravity.
